US00D943357S

(12) **United States Design Patent** (10) **Patent No.:** **US D943,357 S**
(45) **Date of Patent:** **** Feb. 15, 2022**

(54) **BOTTLE**

(71) Applicant: **YETI Coolers, LLC**, Austin, TX (US)

(72) Inventors: **Roy Joseph Seiders**, Austin, TX (US);
Steve Charles Nichols, Austin, TX (US);
Matthew Joseph Petrillo, Austin, TX (US)

(73) Assignee: **YETI Coolers, LLC**, Austin, TX (US)

(**) Term: **15 Years**

(21) Appl. No.: **29/783,713**

(22) Filed: **May 14, 2021**

Related U.S. Application Data

(63) Continuation of application No. 29/741,398, filed on Jul. 13, 2020, now Pat. No. Des. 922,152, which is a continuation of application No. 29/710,243, filed on Oct. 22, 2019, now Pat. No. Des. 889,913, which is a continuation of application No. 29/653,729, filed on Jun. 18, 2018, now Pat. No. Des. 872,542, which is a continuation of application No. 29/618,680, filed on

CLAIM

The ornamental design for a bottle, as shown and described.

DESCRIPTION

FIG. 1 is a top, front, right perspective view of a bottle showing our new design;

FIG. 2 is a front view thereof, wherein the rear view is a mirror image of FIG. 2;

FIG. 3 is a right side view thereof, wherein the left side view is a mirror image of FIG. 3;

FIG. 4 is a top view thereof; and,

FIG. 5 is a bottom view thereof.

The broken lines depicting the remainder of the bottle show features that form no part of the claimed design.

1 Claim, 4 Drawing Sheets

Related U.S. Application Data

Sep. 22, 2017, now Pat. No. Des. 820,650, which is a continuation of application No. 29/605,464, filed on May 26, 2017, now Pat. No. Des. 799,908, which is a continuation of application No. 29/544,197, filed on Oct. 30, 2015, now Pat. No. Des. 804,255.
